UNITED STATES PATENT OFFICE

171,591

NEGLIGEE

Violet Giovagnoni, New York, N. Y.

Application September 28, 1953, Serial No. 26,969

Term of patent 7 years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee, of which the following is a specification, reference being had to the accompanying drawing, forming part thereof.

Fig. 1 is a front view of a negligee, showing my new design.

Fig. 2 is a rear view thereof, on a reduced scale.

Fig. 3 is a fragmentary, slightly enlarged front view illustrating the collar member in raised position, and

Fig. 4 is an enlarged fragmentary portion, illustrating the trim on Figs. 1 and 2.

I claim:

The ornamental design for a negligee, substantially as shown.

VIOLET GIOVAGNONI.
